(57) **CLAIM**
An ornamental design for a shoe with interchangeable heel, substantially as shown and described.

DESCRIPTION

FIG. 1 is a rear perspective view of a shoe with interchangeable heel, showing my new design.
FIG. 2 is a rear elevation view thereof.
FIG. 3 is a right side elevation view thereof.
FIG. 4 is a left side elevation view thereof.
FIG. 5 is a top plan view thereof.
FIG. 6 is a bottom plan view thereof.
FIG. 7 is a rear perspective view thereof, showing the heel portion in detached condition.
FIG. 8 is a top perspective view thereof.
FIG. 9 is a top front perspective view thereof.
FIG. 10 is a rear elevation view thereof.
FIG. 11 is a right side elevation view thereof.
FIG. 12 is a left side elevation view thereof.
FIG. 13 is a top plan view thereof.
FIG. 14 is a bottom plan view thereof.
FIG. 15 is rear perspective view thereof, showing the shoe in detached condition.
FIG. 16 is a rear elevation view thereof.
FIG. 17 is a right side elevation view thereof.
FIG. 18 is a left side elevation view thereof.
FIG. 19 is a top plan view thereof; and,
FIG. 20 is a bottom plan view thereof.

The broken line portions of FIGS. 1-20 are included to show unclaimed subject matter only and form no part of the claimed design.

1 Claim, 11 Drawing Sheets
